UNITED STATES PATENT OFFICE.

JOHN A. BAUER, OF SYRACUSE, NEW YORK, ASSIGNOR TO THE LAMSON COMPANY, OF SYRACUSE, NEW YORK, A CORPORATION OF MASSACHUSETTS.

CENTRAL-STATION DESK FOR CARRIER-DISPATCH SYSTEMS.

Application filed June 20, 1924. Serial No. 721,208.

This invention pertains to pneumatic dispatch systems and more particularly relates to central station apparatus for such systems.

5 In certain types of central station apparatus all carriers, after the necessary transactions of making change, authorizing charge slips, etc., are returned to the sending station from a common dispatch desk. 10 In others, the carriers are returned directly to the sending stations by the cashiers or change authorizers. As business fluctuates from time to time the number of operators at the central station, whether their function be purely that of dispatching carriers or a combination of change making or charge authorizing with dispatching, should be increased or diminished in a corresponding ratio but owing to the physical limitations 15 imposed by the usual types of apparatus it is frequently necessary to retain a greater number of operators at the dispatch desk than is theoretically necessary. This is occasioned in particular by the inability of 20 a single operator conveniently to reach more than a given number of dispatch terminals as they are usually arranged.

The present invention has for its object the provision of dispatching devices for the 25 central station of a pneumatic tube system enabling one or more operators to work with substantially equal facility in dispatching carriers through a given set of terminals and requiring only the simplest type of adjustment in shifting to and from the one operator arrangement, while providing an apparatus capable of embodiment in existing installations without substantial redesign of the latter.

40 A preferred embodiment of the invention together with a modification thereof is illustrated in the accompanying drawings by the way of example.

In the drawings Fig. 1 is a more or less 45 diagrammatic front elevation of a central station desk, of the type wherein the cashiers and charge authorizers dispatch the carriers directly back to the sending stations, embodying the present invention, and viewed from the authorizer's side of the desk;

Fig. 2 is a fragmentary vertical section on the line 2—2 of Fig. 1;

Fig. 3 is a vertical section to larger scale 50 through the upper part of one of the dispatch terminals showing its swivel connection

to the main section of the dispatch tube;

Fig. 4 is a fragmentary horizontal section on the line 4—4 of Fig. 1, but to larger scale;

Fig. 5 is a fragmentary front elevation of the parts shown in Fig. 4; and

Fig. 6 is a fragmentary diagrammatic front elevation of a modified arrangement for adjusting the dispatching terminals.

Referring to the drawings the numeral 1 indicates the central station desk of a pneumatic dispatch system. As illustrated, cash delivery terminals 2 are arranged at the cashier's side of the desk while at the opposite side charge delivery terminals 3 are mounted. While shown as having cashier and charge authorizer's stations at opposite sides, this desk may be considered as exemplifying any desk from which a large number of dispatch tubes lead.

At one side of the desk a plurality of authorizer's stations indicated at 4, 4^a and 4^b, are arranged. The station 4 may for convenience be termed the "main" operator's station while the station 4^a and 4^b may be termed "auxiliary" stations. At the opposite or cashier's side of the desk similarly disposed operators' stations 5 are arranged.

The dispatch terminals are disposed in a vertical plane extending longitudinally and centrally of the desk so that they are within reach of operators seated at either side of the desk. These dispatch terminals, in accordance with the present invention, are disposed in a plurality of spaced groups. The central group or series 6 of delivery terminals is preferably arranged opposite to the main station 4 and fixedly secured in this position. The groups 7 and 8 of dispatch terminals which are spaced laterally from the terminals of the group 6 are normally disposed in front of the auxiliary stations 4^a and 4^b respectively. The terminals of the groups 7 and 8 normally depend vertically 95 in parallelism with the terminals of the group 6 but may be moved laterally relatively to the latter terminals as will herein-after be described.

In Figs. 2 to 5 inclusive, the supporting and adjusting means for the terminals of the groups 7 and 8 is illustrated in detail. Each of the terminals of the groups 7 and 8 extends upwardly in a substantially vertical direction from its lower end to a point above

the upper part of the desk structure and is then curved laterally at 9 to bring its ends into a substantially horizontal position as indicated for example at 7^a in Fig. 3. This horizontal end portion of the terminal is aligned with the horizontally arranged end 10 of the corresponding main tube section leading to one of the sending stations.

The aligned tube sections 7^a and 10 are connected by a sleeve 11 forming a swivel joint which permits the tube terminal to swing about the axis of the tube section 10. The end 7^a of the tube terminal may if desired have an additional support comprising a hanger 12.

The depending vertical portions of the tube terminals are preferably guided in their swinging movement by means of rails 13 and 14 forming parts of the desk superstructure.

The terminals of each of the groups 7 and 8 respectively are connected to each other for simultaneous swinging movement. For this purpose a bar 15 is connected to all of the tubes of the group 7 while a similar bar 16 is connected to all of the tubes of the group 8.

Referring to Figs. 4 and 5 the bar 16 is shown as connected to the tubes of the group 8 by means of bolts 17 whose heads are flush with the inside walls of the respective tubes and whose shanks fit loosely in spaced openings in the bar 16. These bolts are provided with nuts 18 for retaining the bar 16 in position.

The bar 16 extends laterally through a guide opening 19 in one of the end members 20 of the desk frame and is provided with a series of spaced openings 21. By longitudinal movement of the bar any of the openings 21 may be brought into alignment with an opening 22 formed in a block 23 secured to the member 20. When one of the openings 21 is thus aligned with the opening 22 a removable pin 24 may be passed through the openings to lock the bar 16 in adjusted position. The openings 19 and 22 are vertically elongate to permit vertical movement of the bar 16 as the latter swings with the tubes 8.

The bar 15 is likewise pivotally connected to the tubes of group 7 and is likewise provided with spaced openings and a removable pin for retaining it in adjusted position.

When the station is working at full capacity an operator is seated at each of the operator's stations 4, 4^a and 4^b and the groups of terminals are all disposed in vertical position. If now, for example, the amount of work should decrease so that two operators at each side of the desk can care for it, the group 8 of terminals may be swung to the dotted line position of Fig. 1 and locked in this position by means of the pin 24. The operator seated at station 4 may now care for all of the outlying sta-

tions represented by terminals of both groups 6 and 8 of dispatch terminals. Similarly if the work still further decreases the group 7 of terminal 1 may likewise be swung into range of the operator at station 7^a so that one operator at this station may care for all of the charge transactions. It is to be understood of course that the number of cashiers may likewise be diminished at the same time, the dispatch terminals of the several groups being common to both sides of the desk.

In Fig. 6 a slight modification of the device is shown wherein the end portions of the dispatch tubes are vertically arranged and swiveled to the tube ends 10^a by means of sleeves 17^a to turn about vertical axes. The lower ends 26 of the terminals are laterally deflected so that by turning the tube terminals carriers may be delivered in different directions. For turning all of the terminals of a group simultaneously each terminal is provided with a pinion 27 which meshes with a rack bar 28 mounted to slide in suitable guides 29 and 30.

While as indicated in Fig. 1 the terminals of the groups 7 and 8 will be swung toward the terminals of group 6 as the volume of work decreases, it is contemplated that they may also be swung outwardly if the volume of business should increase abnormally, so as to permit two or more operators to be seated in front of each group. It is also contemplated as within the scope of the invention that the terminals of the group 6 may likewise be swiveled to swing either as a single unit or as separate groups so that any desired combinations of groups of tubes may be arranged to accommodate the desired number of operators.

While the movable tube terminals are here shown as dispatch terminals and as depending from a point above the top of the desk it is also contemplated that receiving terminals may be likewise arranged or that any type of terminal may be movably supported in some other manner and from points below or at the level of the desk, the specific mode of supporting the terminals for movement being but a minor feature of the present invention.

I claim:

1. A pneumatic dispatch system having a central station comprising a desk, a plurality of relatively movable tube terminals, and means for positioning said terminals in different grouped aggregations.

2. A pneumatic dispatch system comprising a plurality of groups of movable tube terminals, means connecting the terminals of each group to move as a unit, and means for retaining each group of terminals in selected position of adjustment.

3. A pneumatic dispatch system comprising a plurality of groups of pivotally sup-

- ported dispatch terminals, means connecting the terminals of each group to constrain them to swing concomitantly, and means for locking each group of terminals in selected position of angular adjustment.
4. A pneumatic dispatch system comprising a pivotally supported tube terminal, a bar pivotally secured to the terminal, a guide for the bar, and means engageable with the bar for holding the terminal in selected position of angular adjustment.
5. A pneumatic dispatch system comprising a movable dispatch terminal, a bar connected therewith, the bar having longitudinally spaced openings therein, a fixed guide for the bar, and releasable means optionally engageable with any of said openings in the bar for locking the terminal in selected position of adjustment.
6. A pneumatic dispatch system comprising a movable dispatch terminal, a bar pivotally connected to the terminal, said bar having longitudinally spaced openings therein, a fixed guide for the bar having an opening with which any of the openings in the bar may be registered, and a removable pin engageable with such registered openings to hold the bar and terminal in selected position of adjustment.
7. A pneumatic dispatch system having a central station comprising a fixed tube terminal and a movable terminal adjustable toward and from the fixed terminal.
8. A pneumatic dispatch system having a central station comprising a fixed tube terminal, a movable tube terminal disposed at either side of the fixed terminal, and means for adjustably positioning either one or both of the movable terminals at selected distances from the fixed terminal.
9. A pneumatic dispatch system having a central station comprising a plurality of operators' stations, a plurality of movable tube terminals, and means for moving said terminals simultaneously into operative relation to any of said stations.
10. A pneumatic dispatch system having a central station comprising a plurality of operators' stations, a series of tube terminals each pivoted to swing, and means connecting the terminals of the series to move simultaneously into operative relation to any of said stations.
11. A pneumatic dispatch system having a central station comprising a desk with operators' stations spaced therealong, a series of pivotally supported dispatch terminals depending from a point above the desk, and means for swinging said depending terminals simultaneously to bring them into operative relation to any of said stations.
12. A pneumatic dispatch system comprising a central station desk having a main operator's station and an auxiliary operator's station at one side thereof, a series of fixed tube terminals disposed within reach of the main station, a series of pivotally supported tube terminals normally disposed within reach of the auxiliary station, and means for moving said pivotally supported terminals simultaneously to position them within reach of the main operator's station.
13. A pneumatic dispatch system having a central station comprising a desk, operators' stations spaced along the desk, a series of fixed dispatch terminals arranged in operative relation to one of said stations, a series of movable tube terminals, normally arranged in operative relation to the operators' stations upon either side of the first named station, and means for moving either or both of said last named series of terminals into operative relation to the first named operator's station.
14. A pneumatic dispatch system comprising a central station desk having an operator's station, a series of fixed dispatch terminals disposed in front of said operator's station and within reach thereof, a lateral series of dispatch tube terminals arranged upon either side of the first series, each terminal of each of the laterally disposed series being pivotally supported to depend from a point above the desk, and means for swinging the terminals of either or both of said laterally disposed series into operative relation to said operator's station.
15. A pneumatic dispatch system comprising a central station desk, a plurality of substantially parallel and horizontal pneumatic tube sections each terminating at a point in a plane above the desk, a terminal tube section swivelled to the end of each horizontal section, each terminal section being bent to provide a portion depending vertically over the desk, the depending portions of the several terminal sections being substantially parallel, and means for simultaneously swinging said depending portions and for retaining them in desired position of angular adjustment.

Signed by me at Syracuse, N. Y., this twenty-second day of May, 1924.

JOHN A. BAUER.
